Application March 29, 1954, Serial No. 29,723

Term of patent 3½ years

(Cl. D2—3)

To all whom it may concern:

Be it known that I, Walter D. Hodge, a citizen of the United States, residing at Kansas City, in the county of Johnson and State of Kansas, have invented a new, original, and ornamental Design for a Bulk Beverage Vending Machine, of which the following is a specification, reference being had to the accompanying drawing forming a part thereof, wherein:

Fig. 1 is a front perspective view of a bulk beverage vending machine, showing my new design; and

Fig. 2 is a rear perspective view of a bulk beverage vending machine.

The left-hand side of the machine is identical in appearance with the right-hand side of the machine shown in Figs. 1 and 2.

I claim:

The ornamental design for a bulk beverage vending machine, as shown and described.
